[57] CLAIM

The ornamental design for a corner sink, as shown.

DESCRIPTION

FIG. 1 is a perspective view of a corner sink showing our new design.

FIG. 2 is a top plan view of the corner sink of the invention.

FIG. 3 is a bottom plan view thereof.

FIG. 4 is a front elevational view thereof.

FIG. 5 is a rear elevational view thereof.

FIG. 6 is a left side elevational view thereof; and,
FIG. 7 is a right side elevational view thereof.

The broken line showing is for illustrative purposes only and forms no part of the claimed design.
